UNITED STATES PATENT OFFICE.

ARNOLD SCHROETTER, OF NEW YORK, N. Y.

SAFETY-CATCH FOR PINS AND SIMILAR ARTICLES.

1,370,053.

Specification of Letters Patent.

Patented Mar. 1, 1921.

Application filed September 15, 1920. Serial No. 410,411.

To all whom it may concern:

Be it known that I, ARNOLD SCHROETTER, a citizen of the United States, and resident of the borough and county of the Bronx, 5 city and State of New York, have invented certain new and useful Improvements in Safety-Catches for Pins and Similar Articles, of which the following is a specification.

10 My invention relates to catches whereby the fastening pin or brooches, breast pins, and similar articles are intended to be locked in position, and has for its object to provide a simple construction which includes the various novel features of improvement pointed out in the specification and set forth in the appended claims.

In the accompanying drawings, which illustrate a specific embodiment of the invention without defining its limits, Figure 1 is a rear view of an open-work bar pin provided with my invention; Fig. 2 is a plan view thereof; Fig. 3 is an enlarged detail cross-section on the line 3—3 of Fig. 4; Fig. 4 is an enlarged detail longitudinal section on the line 4—4 of Fig. 3; Fig. 5 is an end view; Fig. 6 is a fragmentary front view and Fig. 7 is a fragmentary inverted plan view.

30 The catch comprises a hook-shaped member 10 formed with a hood 11 which is curved transversely as indicated in Figs. 3 and 5, and longitudinally as shown in Figs. 4 and 7, said hood being extended somewhat beyond the shank 12 of the member 10 to form a projecting abutment 13. The shank 12 is forked to form a pair of bendable prongs 14 constituting a bridge which is located in a plane transverse to the plane 40 of the hook-shaped member 10 or which extends in a direction lengthwise of the usual fastening pin referred to later on, as shown in Fig. 4. These prongs 14 are arranged to be fastened to an article for attaching the catch thereto, and in the case of an open-work bar pin or the like 15, such as shown in the drawings, may be brought into registry with the solid parts or webs thereof and soldered or otherwise connected therewith.

50 By having the prongs located in a plane transverse to the plane of the member 10 or parallel with the usual fastening pin, the attachment thereof to the pin of the illustrated type or its equivalent is facilitated as in this position the prongs are more readily brought into registry with solid parts of the

pin or the like than if said prongs are in a plane parallel with the plane of the hook 10. In practice the usual resilient or springy fastening pin 16 previously mentioned and 60 which is pivoted at 17 to the bar pin 15 or other article is arranged to be engaged with the hook 10 in the manner to be more fully described hereinafter.

The shank 12 is formed with a slot or 65 recess 18 which extends into the member 10 and accommodates a locking member or keeper 19 which is pivoted at 20 and is provided with a finger-piece 21 as shown in Figs. 3 and 5, said locking member being 70 slotted at 22 to form a resilient jaw 23 preferably including as an integral part thereof, a cam 24.

In practice, after the brooch, pin or other article 15 has been attached in place by 75 means of the fastening pin 16, the pointed end of the latter is brought beneath the hook-shaped member 10 or more specifically the hood 11 thereof. The parts are so located and proportioned that in this position 80 the pointed end of said pin 16 will bear against the projecting abutment 13, but preferably not against the hood 11 at the point *a* as shown in Fig. 4; this is not arbitrary as in some cases it may be desirable to have the 85 pin 16 also engage the hood 11 at the point *a*, that section of the pin 16 located between *a* and 13, in any case, being free from contact with said hood. As the locking member or keeper 19 is pivotally moved from the inoperative position shown in Fig. 5 to the operative position illustrated in Fig. 3, the cam 24 will engage the pin 16 and as the pivotal movement is continued, will pass the latter, which finds a seat behind said cam, 90 as shown in Fig. 3. The parts are so proportioned that the locking member or keeper 19, or rather, that part thereof immediately behind said cam 24 flexes said pin 16 or, in other words, places same under a resilient 95 tension either between the abutment 13 and the pivot 17 or between said abutment and the point *a* of the hood 11. In either case, the pin 16 is firmly locked beneath the hook 10 by the elastic tension under which the 100 pin is placed and the resiliency of the jaw 23 and by reason of the same forces, the locking member 19 is held against unintentional pivotal movement out of its operative position; the cam 24 also prevents such unintentional movement of the member 19. To unlock the pin 16, pressure is exerted on the 110

finger piece 21 in a direction to force the cam 24 outwardly beyond the pin 16 and to pivotally swing the member 19 to the in-operative position shown in Fig. 5.

5 A catch constructed as described may be easily applied to a brooch, pin or other article and may be readily manipulated; when in operative position, the catch efficiently locks the pin against accidental or 10 larcenous withdrawal and thus effectively guards the jewelry or other article against loss without in any way complicating its legitimate removal.

Various changes in the specific form 15 shown and described may be made within the scope of the claims without departing from the spirit of my invention.

I claim:

1. The combination of an attaching pin, 20 a hook-shaped member including a hood transversely and longitudinally arched, said pin in its operative position extending beneath and bridging the longitudinal arch of said hood without contacting 25 therewith and engaging said hood only at a terminal point of said arch and a lock-

ing device movably carried by said member and arranged to engage said pin at a point between the terminals of said longitudinal arch and thereby flex said pin against the 30 resistance offered by said hood at the point where it engages said pin whereby the latter is locked against unintentional removal from beneath said hook-shaped member.

2. The combination of an attaching pin, 35 a hook-shaped member terminating in a forked bridge extending in a direction lengthwise of said pin and including a hood, said pin extending beneath said hood and engaging same only in proximity to its periphery, a locking-member pivotally mounted on said hook-shaped member and arranged to flex said pin against the resistance offered by said hood where it engages said pin whereby the latter is locked against 40 unintentional removal from beneath said hook-shaped member and a finger piece carried by said locking-member for manipulating the same.

In testimony whereof I have hereunto set 45 my hand.

ARNOLD SCHROETTER.
